UNITED STATES PATENT OFFICE.

CARL P. C. BRETSCHNEIDER, OF PHILADELPHIA, PENNSYLVANIA.

SHOCK-ABSORBER.

1,084,925.

Specification of Letters Patent. Patented Jan. 20, 1914.

Application filed August 20, 1913. Serial No. 785,609.

To all whom it may concern:

Be it known that I, CARL P. C. BRETSCHNEIDER, of Philadelphia, in the county of Philadelphia and State of Pennsylvania, 5 have invented certain new and useful Improvements in Shock-Absorbers, whereof the following is a specification, reference being had to the accompanying drawings.

My invention is especially intended for use 10 in connection with automobiles, and will, therefore, be described in its relation to the suspending springs which are ordinarily in use in such structures.

In the drawings, Figure I, represents a 15 view in side elevation of the exterior of the device, showing adjacent portions of the spring members connected to the chassis of the vehicle. Fig. II, is a vertical longitudinal section on the line II, II, of Fig. III. Fig. III, 20 is a vertical longitudinal section on the line III, III, of Fig. II. Fig. IV, is a view in perspective of the interior face of one of the side plates which I employ. Fig. V, is a horizontal transverse section on 25 the line V, V, of Figs. II, and III.

One of the principal objects of my invention is to provide a properly responsive cushioning action whose tension may be adapted to the conditions found in a given 30 instance, and to combine the parts in such a manner as to afford the greatest structural strength, while facilitating assemblage, removal and replacement of individual members.

Referring to the drawings, 1, represents the cylindrical external casing at whose lower end is a cap 2, internally threaded to engage with a correspondingly threaded lower portion of the casing 1, as indicated at 35 3. The casing 1, is provided at its upper end with an overhanging integral flange 4, which extends partway across the top, terminating however, in a straight line 5, considerably short of the axis of the casing. The casing 1, is also provided with two vertical brackets 7, and 8, which are preferably cast integral therewith, and which extend some distance above the top of the casing, as shown, the longitudinal center of said 45 brackets being diametrically arranged with relation to the axis of the casing. On the side opposite to the overhanging flange 4, the wall of the casing is cut away as indicated at 10, leaving an opening which is sub-

stantially co-extensive in a vertical direction with the amount of play required for the spring. 55

A cap or cover 12, having a disk shaped upper portion fits snugly between the vertical brackets 7, and 8, and beneath the flange 4. Said cap is provided with a depending flange 13, adapted to overlap and embrace the proximate wall of the casing at the region adjacent to the opening 10, the depth of this flange being such that in the 60 extreme upper position of the cap, the wall 13, will shield said opening. A shallow groove 16, extends diametrically across the cap at the region between the brackets in order to permit convenient application of 65 the supporting spring. Said cover has, on its lower side, a depending cylindrical guide piece 17. Vertical slots 20, and 21, are formed through the walls of the brackets 7, and 8, extending from substantially the level 70 of the top of the flange 4, down to the level of the bottom of the opening 10. Said walls are externally covered by the removable side pieces 25, and 26, which are provided with 75 vertical trough shaped guides 27, and 28. On their internal faces said guides extend 80 through the slots, so that the inner edges of the guide is about flush with the inner face of the brackets. These side pieces are held 85 in position by screws 31, at the lower end and at the upper end by the transverse bolt 32. Spiral springs 34, and 35, having their coils disposed in inverse relation, are 90 arranged within the casing, the inner spring 35 embracing the depending guide piece 17. 95 of the cap 12. The lower ends of said springs bear upon the removable cap 2, while the upper ends bear against the end surfaces of the cap 12. A transverse bolt 36, extends across between the brackets 7, and 8, at the region immediately adjacent to the top of the cap 12, the ends of said bolt being received within the guides 27, and 28. 100 Said bolt is, therefore, susceptible of vertical play along with the cap in said guides. A second transverse bolt 32, is rigidly secured across between the upper ends of the brackets, said bolts, as before stated, serving to retain in position the upper 105 ends of the side pieces 25, and 26. The upper spring member 40, of the vehicle is attached to this lower bolt 36, while the lower spring member 41 of the vehicle is at-

tached to the upper transverse bolt 32, the ends of said springs embracing said bolts respectively.

In assembling the device one of the side plates 25, or 26, is removed and after the spring member 40, is placed in position, the bolt 36, is inserted laterally, and the side piece is then secured in position. As will be seen from the above description, the other portions of the device are readily assembled and removed.

In operation the lower cap 2, can be adjusted at different heights, so as to modify the tension of the springs.

15 In operation the vertical play of the upper cap 12, within the limits afforded by the overhanging flange 4, and the bottom of the opening 10, corresponds with the required range of movement permissible for 20 the spring device, and it will be noted that the wall 13, at all times completely incloses the opening 10, so that access of dirt is prevented.

Having thus described my invention, I 25 claim:

The combination of the cylindrical casing,

having a screw cap, at its lower end, and provided with a limited overhanging flange at its upper end; and also provided with a vertical opening in the wall opposite to said flange; vertical brackets diametrically arranged with relation to said casing, said brackets being provided with vertical slots; removable side plates provided with guides which fit within said slots, and means for attachment to said brackets; a cover having an axial depending guide, and a lateral depending wall, the latter being adapted to inclose the opening in the casing; a transverse bolt extending diametrically across the cover and engaged at each end in the guides of the side pieces, and a second transverse bolt rigidly secured near the upper extremities of the brackets substantially as set forth.

In testimony whereof, I have hereunto signed my name at Philadelphia, Pennsylvania, this eighteenth day of August, 1913.

CARL P. C. BRETSCHNEIDER.
